D12-20. OR D 13,406 EX

No. 13,406

Nov 14, 1882

UNITED STATES PATENT OFFICE.

JOHN L. POPE, OF CLEVELAND, OHIO.

DESIGN FOR A WHIFFLETREE-PLATE.

SPECIFICATION forming part of Design No. 13,406, dated November 14, 1882.

Application filed August 24, 1882. Term of patent 14 years.

To all whom it may concern:

Be it known that I, JOHN L. POPE, of Cleveland, in the county of Cuyahoga and State of Ohio, have invented and produced a new and original Design for Whiffletree-Plates, of which the following is a specification, reference being had to the accompanying engraving, forming part thereof.

My invention relates to a design for whiffle-tree-plates; and it consists in the shown shape of the parts of same, as will be hereinafter more particularly explained and claimed.

In the engraving which accompanies this specification, A represents one half and B the other half or part of a pair of whiffletree-coupling plates. The half A has a cup-shaped part or socket, *a*, round in contour, with a hole at its bottom, through which the usual pivot-bolt passes. The bottom of cup-shaped part is not flat, but is sloping from the top of the raised ring or collar *i* down to the root of the inner periphery of the cup *a*. On either side of the socket *a* is an ear-piece perforated with two holes, so as to adapt the part for securement to the trees or cross-bar of a vehicle. The contour of one of these ear-pieces, it will be seen, is like the other in every respect. At the outer extremity is a rounded arch, *b*. Then both the edges are curved inwardly or contracted, as at *c*,

then curve outward as at *n*, and then flare 30 farther outward in substantially a straight line until the cup-shaped part is met. The part B is provided with ear-pieces similar in contour to those on the part A, and has the usual central bolt-hole and holes for fastening-screws. It is further provided with a stud, *e*, which fits into the large central bolt-hole when the parts are coupled together for use, and, besides, has a boss, *m*, that rests on the ring *i* when the parts have been brought into the 40 condition just above described. It will be understood of course that the central hole in part B extends through the body of plate and through the boss and stud, so as to permit the pivot-bolt to pass through and properly couple 45 together the parts A and B.

What I claim as my new design, and desire to secure by Letters Patent, is—

1. The part A, having the cup portion and ear-pieces, shaped as described and shown. 50
2. The part B, with ear-pieces, curved as shown and described.

In witness whereof I have hereunto set my hand this 5th day of August, 1882.

JOHN L. POPE.

In presence of—

J. R. CURRIER,
J. M. ODELL.
